ELECTRICAL JUNCTION DEVICE

Leo J. Werner, Arlington, N. J.

Application June 1, 1938, Serial No. 211,165

7 Claims. (Cl. 173—324)

This invention relates to an electrical junction device for the purpose of joining a plurality of wires carrying electrical current to or from a machine, switchboard, or some other electrical instrument.

It is the object of my invention to provide an electrical junction device which will enable a maximum number of wires to be brought together at the junction point in the smallest possible space and at the lowest cost.

Other and further supplementary objects will be seen from a study of the specification taken in connection with the annexed drawing, wherein:

Figure 1 is a plan view of one form of my improved junction device, a part of the cover and number plate being removed.

Figure 2 is a side elevation of Figure 1.

Figure 3 is a bottom plan view of Figure 2.

Figure 4 is a section on the line 4—4 of Figure 2.

Figure 5 is a section on the line 5—5 of Figure 2.

Figure 6 is an enlarged view, part in section and part in elevation, showing certain details of the junction device.

In the various views wherein like numbers refer to corresponding parts, 1 is a block of insulating material which has a plurality of cross or transverse bores 2, within which are positioned metallic connectors 3. As will be seen from Figure 2, the bores 2 are arranged in a plurality of spaced rows and the holes themselves are arranged in staggered relation, one to the other, in the respective rows. By this arrangement the greatest number 35 of connectors 3 can be assembled in a given size of insulating block, at the same time giving sufficient insulation between the walls of the adjacent bores.

The connectors 3 are hollow or provided with 40 holes therethrough to receive the bared ends 4 and 5 of insulated conductors or cables 6 and 7. As will be seen from Figures 2 and 6, the connectors 3 have the holes therein preferably eccentric so as to provide a thin wall 8 which may be indented as at 9, the indentation 9 acting as a 45 stop for the bared ends 4 and 5 of the said conductors. The ends 4 and 5 are engaged by their respective screws 10 and 11 which are positioned in holes 12 provided in the block 1.

As shown in Figure 1, the connectors 3 are 50 preferably alternately offset, and likewise, the holes 12 for the screws 10 and 11. This also insures a maximum amount of insulation between the screws 10 and 11. Also as shown in Figure 1, the bores for the connectors 3 are made so as

to be only slightly larger than the conductors 6 and 7, so that the insulation of the conductors extends fully within the block 1 and substantially fills the bores made for it. In this way the insulation is prevented from fraying and there is 5 no chance of contacting with the live parts of the junction device. This arrangement also acts to keep moisture out of the connection and lessens corrosion and electrolytic disintegration at the 10 connector.

Where a plurality of taps are desired to be made from one feed wire coming to the junction device, the bottom thereof is made with a channel 13, in which a metallic plate 14 is positioned, being held in place by screws 15 which go into cooperative connectors 3 and are so positioned therein, as indicated in Figures 3 and 4, as to act, in each case, as a stop for the conductor ends, similar to the indentation 9 of Figure 6. By making the plate 14 of sufficient length, as many 20 taps may be taken off from one lead wire as are desired.

In covering the holes 12, I use a designation strip 16 over which is positioned a transparent plate 17, the same being held to the block in any 25 satisfactory manner as by screws 18. As shown in Figure 1, the block 1 may be formed at one or both ends with lugs 19 having screw-holes 20 therein for mounting purposes, or the block 1 may be provided at one or both ends with bosses 21 30 on its lower surface and mounted by a screw-hole 22 from an under-support; or the combination of the two may be used as shown in Figure 2. As a matter of fact, the block may be formed to fit any 35 desired mounting so that the junction device may be used in an outlet box for socalled BX cable, or may be mounted to act as a terminal block for motors and generators; or arranged for any other type of mounting. It follows, of course, that the junction device may be made with any number 40 of bores and supplied with their respective connectors to suit conditions; for example, for certain classes of work there may be as many as two, three and four dozen connectors mounted within the block, while for a motor only two or three 45 connectors will be required. By making the blocks 1 with mounting bosses such as 21, contact with the mounting surface area is reduced and the possibility of moisture collecting on the 50 block is thereby largely eliminated.

From what has been said, it will be understood that various changes may be made in the mounting arrangement of the block and the parts carried thereby, without departing from the spirit of 55

the invention and the scope of the appended claims.

What I claim is:

1. An electrical junction device comprising a block of insulating material having a plurality of spaced longitudinal rows of parallel transverse bores of uniform diameter extending all the way through the block and arranged in spaced and staggered relation, metallic connectors removably located in said bores, each connector having an eccentrically located longitudinal hole therethrough thereby having thin and thick wall portions, the thin wall being indented to form a conductor stop midway between the ends of the connector, the thick wall portion having screw-threaded holes therethrough near the opposite ends of the connectors, clamping screws located in said screw holes, the connectors being materially shorter than the width of the block and the length of the bores, the block having holes leading from an easily accessible face of the block into the bores for said clamping screws, the holes and screws therein locating the connectors in the bores so the ends of the connectors are spaced a substantial distance from the ends of the bores as and for the purpose described. 5
2. An electrical junction device as set forth in claim 1, further characterized in that the connectors fill the bores in which they are located throughout the length of the connector while the bores are of a diameter such that the insulation, on the conductor to be used with a given connector, fills the bore at opposite ends of the connectors. 10
3. An electrical junction device comprising a block of insulating material having parallel bores extending transversely entirely through the block, metallic connectors located in said bores but terminating a substantial distance from opposite ends of the bores and filling the bores for the length of the connectors, each connector having a longitudinal eccentrically located hole therethrough, thereby having thick and thin wall portions, the block when installed in position having holes leading from one easily accessible face to the bore, clamping screws located in said holes in the block and in the thick-wall portion of the connector at opposite ends thereof, and stop means intermediate the ends of the connector and located in the thin-wall portion for positioning a conductor in the connector. 15
4. An electrical junction device comprising a block of insulating material having circular cross-bores therethrough, a metallic connector slidably fitting snugly within each bore and terminating well within the interior of its bore, at least one hole extending from the face of the block to each bore, a screw for each hole and being screw-threaded into its connector to hold the connector in place, said connector having a hole therethrough to receive a conductor to be clamped by said screw, and means for taking off a plural number of taps from one connector and its associated conductor, said means including a metallic strip located in a channel on a side of the block, with screws going through the plate into all the connectors desired to be cross-connected for the outgoing taps. 20
5. An electrical junction device as set forth in claim 4, further characterized in that the plate screws enter their respective connectors substantially midway of their ends and act as stops for the conductor ends. 25
6. An electrical junction device comprising a block of insulating material having a plurality of spaced longitudinal rows of transverse bores arranged in spaced and staggered relation, a metallic connector having a longitudinal hole therethrough and located in each bore and having a length materially shorter than the length of the bore for the purposes described, each connector having a clamping screw at each end for clamping a bare conductor in the connector, the face of the block having holes leading into the bores for access to said clamping screws, means for taking off a plural number of taps from one conductor and its connector, said means including a metallic plate located in a channel in the bottom of the block and having screws going one each into each consecutive connector including the connector having said one conductor fastened thereto thereby connecting them all in parallel, 30 said plate screws entering the hole in the respective connectors at approximately the midpoint thereof and acting as a stop for the bare conductor ends, and a covering and designation strip attached to the block over said connector screw holes. 35
7. An electrical junction device comprising, a block of insulating material having circular cross-bores therethrough, a metallic connector slidably fitting snugly within each bore and terminating well within the interior of its bore, at least one hole extending from a side of the block to each bore, a screw for each hole and being screw-threaded into its connector to hold the connector in place, said connector having a hole therethrough to receive a conductor to be clamped by said screw, and means for taking off a plural number of taps from one connector and its associated conductor, said means including a metallic strip located in a channel on a side of the block, with screws going through the plate into all the connectors desired to be cross-connected for the outgoing taps. 40
